UNITED STATES PATENT OFFICE.

ALOIS A. RITTER, OF RACINE, WISCONSIN, ASSIGNOR TO HARTMANN TRUNK COMPANY, OF RACINE, WISCONSIN, A CORPORATION OF WISCONSIN.

DESIGN FOR TEXTILE FABRIC.

Application filed August 25, 1928. Serial No. 27,963. Term of patent 7 years.

To all whom it may concern:

Be it known that I, ALOIS A. RITTER, a citizen of the United States, residing at Racine, in the county of Racine and State of Wisconsin, have invented a new, original, and ornamental Design for Textile Fabric, of which the following is a description, reference being had to the accompanying drawing, forming part thereof.

The lining on the drawing indicates contrasting shades of the same color.

In the drawing, the figure is a plan view of a piece of the textile fabric, showing my new design.

I claim:

The ornamental design for textile fabric, as shown and described.

ALOIS A. RITTER.
